DISPLACEABLE TARGET GAME

Henry F. Wheeler, Richmond Heights, Mo., assignor of one-half to A. Edward Gross, Richmond Heights, Mo.

Application May 28, 1945, Serial No. 596,153

5 Claims. (Cl. 273—102)

1

This invention relates to target games. A primary object is to create an interesting toy target game lacking the usual relatively high costs of manufacturing and assembling the various details.

A further object is to provide for special interest in aiming and shooting at the simple target device.

Another object is to produce a simple toy shooting device having cooperative details for the exercise of skill and attention in aiming toward a toy target.

With the foregoing and other objects in view, the invention comprises the specific combination and arrangement of details herein shown to illustrate one form of the invention. However, it is to be understood that the patent on this invention extends to all modifications more broadly described by terms employed in the claims hereunto appended.

Fig. 1 is a top view of the target device and its separately adjustable shooting device.

Fig. 2 is a section taken approximately on the line 2—2 in Fig. 1.

Fig. 3 is an enlarged detail top view showing a slot in the top of the target support, and the top of a target sheet loosely arranged at an angle to said slot, so as to rest upon top surfaces at opposite sides of the slot.

Fig. 4 is a companion side view of the target sheet shown in Fig. 3, with full lines showing the normal elevated position of the target, and dotted lines for the lower position, the target support being shown in section.

Fig. 5 is a view similar to Fig. 4, showing a separately adjustable baffle member.

Fig. 6 is a vertical section on the line 6—6 in Fig. 5.

Briefly stated, the target device comprises a support 7 having any desired number of slots 8 to receive the targets. In some cases only one slot may be employed for only one target, but a more interesting game seems to appear in the use of a plurality of slots 8 for the reception of targets, freely movable from one slot to another, so as to vary the locations of the targets. Fig. 1 shows relatively short slots 8, each adapted to receive only one target, and an elongated slot 9 where a plurality of targets may be readily arranged in different positions. I prefer to provide for such variations by forming a group of slots, of any desired length, that will enable the targets to be selectively located in various positions.

I have shown a plurality of targets 10 in Fig-

2

ures 1 to 4 inclusive. Each of these targets 10 has a lower anchoring member 11 in the form of a relatively narrow vertical tongue extending downwardly through one of said slots, so as to lie below the slotted support 7. Each of said targets 10 is also provided with extended abutment members 12 to be loosely seated on the top of said support 7, at opposite sides of said lower anchoring member 11. To understand this point, the details of Figures 3 and 4 should be considered. The extensions 12 have bottom abutment edges which are located in oblique positions and loosely seated at opposite sides of the slot 8 shown in Figures 3 and 4.

When a projectile is discharged onto any part of the target 10 (Figures 3 and 4) there will be a vibrational displacement of the target, which usually allows upper portions of the target to drop into the relatively wide slot 8, as suggested by dotted lines in Fig. 4. No special accuracy is required in making this simple target device. Each elongated slot is substantially wider and longer than the elongated target, said target being located at an acute angle to the adjacent slot, so as to occupy an oblique position across a relatively wide slot, as shown most clearly at 8 and 10 in Fig. 3. The target is thus supported on its oblique abutment edges at the bottoms of the members 12 which extend from opposite sides of the depending member 11. In this specific arrangement of details, the target 10 is movable from its oblique position (Fig. 3) to a displaced position parallel with the slot 8, thereby shifting the oblique abutment edges from positions at opposite sides of the slot to positions directly above said slot, so as to drop the target into the slot.

More specifically stated, an extremely simple and very interesting device of this kind may include a simple box made of paper or other inexpensive sheet material having its details arranged as shown in Figures 1 and 2, said box having a supporting wall 7 provided with a group of slots to receive the targets, a lower wall 13 below said wall 7, and relatively narrow deflecting walls 14 and 15 extending downwardly from the sides and rear of said slotted supporting wall 7 to form the side and rear walls of the box.

The simple targets 10 can be made of inexpensive sheet material exposed above and below the slots 8, while loosely seated at opposite sides of the respective slots, and there may be excess spaces at the slots to provide for selective variations in arranging the target sheets.

The lower target members 11 are preferably exposed below the slotted supporting wall 7, and

in testing this form of the invention, I have found it desirable to provide for free rocking movements at the lower ends of said target members 11, as shown by the curved lower edge 16 in Fig. 4.

Another detail of interest to those who aim at the lower extended target members 11 (Figures 2 and 4) appears in a relatively large baffle sheet 17 shown in Figures 5 and 6. This baffle sheet 17 is freely movable into and out of any of the slots 8 and 9, and it has an enlarged extension 18 to be removably seated on the top of the supporting sheet 7. The extension 18 is preferably curved at the bottom to provide for free rocking movements when the baffle 17 is hit by a projectile. However, the player derives no credit score for striking this large baffle sheet 17. Said sheet 17 is to be selectively located in front of a selected target member 11 and thereby give a special score to a player who causes the projectile to rebound from one or more of the deflecting walls 14 or 15 (Fig. 1), and then strike a target member 11 behind the large baffle 17.

A very desirable cooperative detail of this game appears in the shooting device shown in Figures 1 and 2. This device comprises a cylinder 20 from which toy projectiles 21 are discharged toward the loose targets. The cylinder 20 has a flat base and it is freely slideable to any desired aiming position on the table top 22 (Fig. 2) which supports the target device. Said cylinder 20 has an upwardly extending recess 23, open at the top to provide a sight opening, an inclined mirror 24 confined within said sight opening as shown in Fig. 2, and a horizontally disposed opening 25 at the front of said inclined mirror exposed in the direction of discharge from said cylinder. The openings and mirror are arranged for aiming the projectiles toward selected portions of the targets.

The cylinder 20 is provided with a longitudinal bore 26, and a plunger rod 27 slideable therein to discharge the projectiles. A magazine 28 extends upwardly from the path of said plunger to receive a vertical row of projectiles, preferably in the form of balls 21. As shown in Fig. 2, this magazine is open at the top to receive the projectiles, and the lowest projectile normally rests upon the top of the plunger 27. However, this plunger has an operating member 30 at its outer end to be grasped and pulled to the left of the position shown in Fig. 2, thereby releasing the balls 21, and allowing the lowest ball to drop into a recess 31 at the bottom of the bore 26. Any suitable spring device may be employed to forcibly discharge the projectile when the operating member 30 is released. For example, a metallic spring or a strip of rubber 32 may connect the plunger rod 27 to the cylinder 20, as shown in Fig. 2. It will be observed that the shooting device comprising the freely slideable cylinder 20 carrying the mirror 24, is universally adjustable to any desired aiming position in front of the open margin of the target device.

The box which normally supports the targets may be conveniently employed as a container for shipment or storage of the loose target members, and the closed rear portion of this box may be provided with feet 34 as shown in Figures 1 and 2, to form an inclined bottom for free return of balls to the open front portion of the box. In Fig. 2, the front edge of the inclined bottom 13 is beveled to avoid the presence of an abrupt obstruction at this edge.

In the cooperative arrangement of specific details shown by Figures 1 and 2, the shooting de-

vice is a separate and distinct unit having no attachment to the box which supports the target sheets. This shooting device is freely slideable on the separate table top 22 (Fig. 2) to any desired aiming position beyond the open front of said box, so as to provide for universal adjustment in aiming at selected target members 11, or in carefully aiming toward one of the abutment walls 14 or 15 from which the projectile may rebound and strike various targets, including a target member 11 behind the large baffle 17.

The sight opening 23 (Figures 1 and 2) is formed in an upward extension 35 integral with but in front of the magazine 28, and between the magazine and the discharge end portion of the cylinder 20, so that the magazine will not interfere with sighting through the mirror. This mirror 24 may be confined in the sight opening 23 at an angle of about 45 degrees.

I claim:

1. A target game comprising a supporting sheet having elongated slots to receive the displaced targets, a plurality of separate target sheets made of material thin enough to move into and out of said slots, each of said separate target sheets having exposed upper portions located above the top of said supporting sheet, and a lower missile receiving member extending downwardly from said exposed upper portions, so as to extend through one of the slots and lie below the supporting sheet, the exposed upper portions of each target sheet being elongated and provided with extensions at opposite sides of its lower missile receiving member, the extensions being located at an acute angle to and loosely seated at opposite sides of the slot, so as to loosely support the target sheet at said opposite sides, and the lower missile receiving members of the targets being exposed below said supporting sheet to receive projectiles from a shooting device.

2. A target game comprising a support in the form of a box having elongated slots in its top wall to receive the displaced targets, a plurality of separate targets each having extended abutments located at an acute angle to the slots and loosely seated on the top of said top wall, at opposite sides of one of said slots, so as to movably support the targets, and a lower target member extending downwardly between said abutments so as to extend through and lie below the slot, the loosely seated targets being movable into said slots in response to displacements of their extended abutments, said box being open at one edge of expose the lower target members, and thereby provide for aiming toward said lower target members.

3. A target game comprising a support in the form of a box having a supporting wall provided with elongated slots to receive the displaced targets, a lower wall below said slotted supporting wall, and relatively narrow deflecting walls extending downwardly from the sides and rear of said slotted supporting wall to deflect the missiles and form the side and rear walls of the box, the front of said box being open to receive and return projectiles discharged toward the targets, a plurality of separate targets, each having extended abutments located at an acute angle to the slots and loosely seated on the top of said slotted supporting wall at opposite sides of one of said slots, so as to loosely support the targets, and a lower missile receiving member extending downwardly between said abutments so as to extend through and lie below the slot,

the lower missile receiving members being exposed below said slotted supporting wall.

4. A target game comprising an approximately horizontal supporting sheet having a group of slots to receive the targets, a group of separate target sheets made of sheet material thin enough to move into and out of said slots, each of said separate target sheets having exposed upper portions located above the top of said supporting sheet, and a lower target member extending downwardly from its exposed upper portions, so as to extend through one of the slots and lie below the supporting sheet, the exposed upper portions of each target sheet being provided with extensions at opposite sides of its lower target member, the extensions being loosely seated at opposite sides of the slot, so as to loosely support the target sheet at said opposite sides, and a detachable baffle sheet movable into and out of selected slots of said supporting sheet to interfere with aims toward selected target members, said detachable baffle sheet having an extension removably seated on said supporting sheet.

5. A target game comprising an elongated target, a support having an elongated slot into which the target is dropped, said slot being substantially wider and longer than the target, said target being located at an acute angle to said

slot so as to occupy an oblique position across the elongated slot, said target having a depending member located within the slot, and oblique abutments extending from opposite sides of said depending member so as to rest upon top portions of the support at opposite sides of said elongated slot, and said target being movable from said oblique position to a displaced position parallel with the elongated slot, thereby shifting said oblique abutments to positions directly above said elongated slot.
